DESIGN FOR A BOTTLE OR SIMILAR ARTICLE

Thomas F. Smith, Elm Grove, W. Va., assignor to L. Perrigo Company, a corporation of Michigan

Application December 5, 1938, Serial No. 81,592

Term of patent 14 years

To all whom it may concern:

Be it known that I, Thomas F. Smith, a citizen of the United States and residing in the town of Elm Grove, in the county of Ohio and State of West Virginia, have invented a new, original, and ornamental Design for a Bottle or Similar Article, of which the following is the specification, reference being had to the accompanying drawing, forming a part thereof.

On the drawing:

Fig. 1 is a plan view illustrating the bottle embodying the design of my invention.

Fig. 2 is a front view of my invention.

Fig. 3 is an edge view thereof.

I claim:

The ornamental design for a bottle or similar article, substantially as shown.

THOMAS F. SMITH.
